[57] CLAIM

The ornamental design for a vehicle top, as shown and described.

DESCRIPTION

FIG. 1 is a side elevational view of the vehicle top showing our new design, the broken lines being for illustrative purposes only;

FIG. 2 is a rear elevational view thereof;

FIG. 3 is a front elevational view thereof; and

FIG. 4 is a top plan view thereof.

The side of the vehicle top opposite to that shown in FIG. 1 is a mirror image thereof.
